VENETIAN BLIND

Donald J. Croxen, Lawndale, Calif.

Application October 26, 1953, Serial No. 388,194

2 Claims. (Cl. 160—173)

1

The present invention relates generally to a Venetian blind structure and relates more particularly to a Venetian blind slat arrangement for providing a nearly light-tight closure for windows and the like. The present invention contemplates the use of a plurality of crowned slats that are adapted for edge-to-edge contact when moved to a closed position, thereby to prevent the passage of light thereabout, while still retaining the relative simplicity of such blinds and operating mechanism thereof.

Heretofore, Venetian blind structures have utilized a plurality of slats supported on various types of tapes, cross bars, and lift cord arrangements, these arrangements necessarily extending intermediate the slats and tending to hold such slats in spaced relationship when in a closed position. This prior construction permitted the passage of a sufficient amount of light between the slats, as to prohibit the use of such closures in situations requiring the darkening of rooms or the like. For example, in classrooms, it is often desirable to darken the room to enable projection and viewing of motion pictures or slides. Heretofore, it has been necessary to provide the windows of such classrooms with auxiliary curtains, drapes or shades in order to accomplish such darkening, while still retaining conventional Venetian blinds. This additional equipment has been necessarily expensive and often unattractive, thus establishing the desirability for more efficient light control means for the Venetian blinds.

Prior attempts at a solution to this light passing problem in Venetian blinds have included relatively large longitudinal notches in the edge of each slat, these notches being of a length wider than the combined width of two adjacent cross bars or tapes and the lift cord to permit movement of the slats into a closed position. Such construction presents open areas that are either not used or not filled with operating or supporting structure when the blind was closed, thereby to permit the passage of undesirable light there-through.

With reference to the drawing:

Figure 1 is a perspective view taken from the rear of a Venetian blind structure of the present invention;

Figure 2 is a fragmentary sectional view taken substantially as indicated by the line 2—2, Figure 1, and showing the edge-to-edge contact attained by the slats utilized in the present invention;

Figure 3 is a perspective view showing a plurality of adjacent slats;

2

Figure 4 is a sectional view taken substantially as indicated by line 4—4, Figure 1;

Figure 5 is a sectional view of the slats taken at the connection of the support tapes to the tilt bar with the slats shown in an open position; and

Figure 6 is a fragmentary transverse sectional view taken substantially as indicated by line 6—6, Figure 5.

In the drawing, with reference primarily to Figure 1 thereof, the Venetian blind structure of the present invention is shown as indicated generally at 10. As shown, the upper portion of the blind is adapted to be supported by a suitable valance box 11 having side portions 12 and 13 and end caps or boxes 14. In accordance with conventional practice, the valance box 14 is adapted to be secured adjacent the upper portions of a window or the like. The boxes 14 are adapted to house suitable conventional blind operating mechanisms 15. The mechanism 15 may be operatively secured to a tilt bar 16, Figures 4 and 5, the detail construction thereof to be hereinafter more fully described.

It is to be clearly understood that, while the present Venetian blind structure is shown and will be described in connection with a specific valance box and associated supporting structure, the invention has many applications in connection with a variety of like arrangements.

The Venetian blind structure comprises a plurality of slats and supporting structure therefor that is indicated generally at 17 and adapted to be supported from the upper end thereof as by any suitable conventional attachment means. The sides or ends of the various slats may be disposed intermediate vertically extending channel members 18 to prevent the passage of light about the end portions of the blind. The members 18 may be secured adjacent the opposite ends of the slats by any suitable means desired so long as they surround or embrace the outer extremities of the blind.

The blind structure 17 is composed of a plurality of relatively thin elongated slat members 19. These slat members may be made from metal, plastic, wood, or the like and are preferably crowned, as best shown in Figure 2. The slats 19 are adapted to be supported in normally spaced relationship by means of vertically disposed front and rear main supporting tapes 20 and 21 arranged on each side of the plurality of slats. The upper ends of the tapes 20 and 21 may be suitably secured to the tilt bar 16 that is rotatably supported within the valance box 11, as shown primarily in Figure 5. A plurality

of cross tapes 22 are secured to and/or formed from the tapes 20 and 21, and extend between said main tapes, the slats 19 being adapted to be supported by and rest on these cross tapes. As shown primarily in Figure 1, the cross tapes 22 are arranged in staggered relationship to each other and disposed on opposite sides of the centerlines of the main supporting tapes 20 and 21, in order thereby to reduce mechanical interference one with the other when the blind structure is moved from one position to another. A space is thus presented transversely intermediate the cross tapes for placement of other supporting and operating mechanism to be hereinafter described.

The cross tapes 22, being connected to the main supporting tapes 20 and 21 at equally spaced points to form ladders are substantially parallel and are all substantially horizontal at what may be termed the maximum open position of the slats 19 shown in Figure 5. A feature of the invention is that the tilt bar 16 is transversely inclined upwardly and rearwardly from the horizontal, as shown in solid lines in Figure 5, when the cross tapes 22 are substantially horizontal. As may be seen in Figure 5, this relationship between the tilt bar 16 and the cross tapes 22 is provided by connecting the tilt bar to the front supporting tape 20 by an upper end portion 20a of the supporting tape that is relatively short as measured upward from the uppermost cross tape 22, and by connecting the tilt bar to the rear supporting tape 21 by a longer end portion 21a of the rear supporting tape 21.

In order to provide the light-restricting seal contemplated by the present invention, as shown primarily in Figures 3 and 6, each of the slats 19, adjacent opposite ends thereof, is provided with cutouts 23 in the rear edges thereof which may be referred to as first marginal notches. The cutouts 23 are substantially rectangular and adapted, adjacent one longitudinal end portion thereof, to accommodate the staggered cross tapes 22. The cutouts in adjacent slats 19 have portions that are staggered to correspond to the staggered relationship of the cross tapes 22, thereby to reduce the size of such cutouts and eliminate the beforementioned unnecessary openings that would normally admit undesirable light therethrough.

In accordance with conventional practice in the manufacture of Venetian blinds, each of the slats 19 is provided with transversely extending elliptical apertures 24 through which a lift cord 25 is adapted to extend. The apertures 24 are in vertical alignment in adjacent slats 19, in transverse alignment with end portions 26 of the cutouts 23 and formed forwardly from the longitudinal centerline of the slats 19. The end portions 26 of the cutouts which intercept the extended axes of the elongated apertures 24 are in vertical alignment in adjacent slats 19 and adapted to accommodate the lift cord 25 when the blind is moved to a closed position. It may further be seen that the end portions 26 of the cutouts and the openings 24 are substantially transversely aligned and positioned in the open space between the cross tapes 22.

When the Venetian blind is moved to a closed position with the rear edges of the slats 19 directed downwardly, the cross tapes 22 and the lift cord 25 will be disposed in the cutouts 23, thus to permit full closure of the blind structure in a manner shown primarily in Figures 2 and 4. It is to be noted that as the blind is moved to-

ward a closed position, and as the tilt bar 16 moves in a clockwise direction from the solid line position to the dotted line position in Figure 5, the shorter front supporting tape 20 will be pulled taut while the rear tape 21 will be slackened. As shown, the tilt bar 16 rotates to a position in the order of six degrees past the vertical of the blind structure. The rotation of the tilt bar 16 past a vertical position, through the shortened front tapes induces a rotational force in each slat that exceeds that encountered in conventional blind construction to force the rear edges of the slats into positive engagement with the convex surface of adjacent slats. As the slats are thus forcibly moved into the closed position, the depth of the notches 23 can be held to a minimum.

In an open position, as shown in Figures 5 and 6, the rear edges of the slats 19 are adapted for suspension on the tapes 22 at points adjacent the rear main supporting tape 20 with the inner edge 27 of the cutouts 23 engaging the tapes 22.

In order to insure constant precise alignment of the cross tapes 22 with the staggered cutouts 23, as shown in Figures 3 and 6, each of the slats 19 is provided with a pair of T-shaped slots 28 in the front edge thereof and remote from the cutouts 23. These T-shaped slats may be referred to as second marginal notches. The slots 28 are staggered in relation to each other in adjacent slats 19 and adapted to receive the cross tapes 22 in a manner permitting the cross tapes to be slidable therein as may be necessary when moving the slats from one position to another. The slots 28 are of a width just sufficient to permit reception and free movement of the tapes 22, while still preventing excess light from passing thereabout. Each of the slots 28 has one end thereof in transverse alignment with the corresponding end of the adjacent cutout 23, thus to guide the slats 19 and insure constant disposition of the cross tapes 22 in the cutouts 23. These slots 28 also permit a reduction in the width of the cutouts 23 as might otherwise be required to insure the constant alignment of the tapes 22 therein.

The slots 28 also form, as best shown in Figure 6, pair of oppositely directed tongues 29 having their adjacent ends spaced apart to facilitate reception of the cross tapes 22 into the slots 28. The tongues 29, once the tapes 22 are disposed in the slots 28, act to hold the slats against pivotal movement relative to the cross tapes. This construction thus prevents movement of the slats by reason of drafts or wind currents as well as careless handling of the slats by occupants of the room in which the blinds are mounted.

As shown in Figure 3, each end of the slats 19 is provided with a group consisting of a cutout or first marginal notch, elliptical opening or aperture and T-shaped slot or second marginal notch which will cooperate to accomplish the purpose of the present invention. These necessary open areas through the slats are formed in such a manner as to reduce light passing openings to a minimum and to present no open areas that are not used in the maintenance of effective and reliable operating characteristics for the blind. The group of openings at each end of the slats 19 are reversed in order to maintain uniformly manufactured articles.

Having thus described the invention and the present embodiment thereof, it is desired to emphasize the fact that other modifications may

be resorted to in a manner only limited by a just interpretation of the following claims.

I claim:

1. A set of slats of curved cross sectional configuration for use in a full-closure Venetian blind having at least two lift cords and at least two corresponding pairs of vertical supporting tapes with the vertical tapes of each pair interconnected by cross tapes to form at least two ladders, and with the cross tapes narrower than the supporting tapes and staggered alternately on opposite sides of the center lines of the supporting tapes, each of the slats of said set having a group of openings for cooperation with each of said ladders and the corresponding lift cord, one of said openings of each group being an elongated aperture for said lift cord with the axis of the aperture extending transversely of the slat, said aperture being positioned to one side of the longitudinal center line of the slat, another of said openings of each group being a first notch in the margin of the slat to the other side of the longitudinal center line of the slat for one end of one of said cross tapes, the dimension of said first notch longitudinally of the slat being greater than the width of a cross tape but less than twice such width, with an end portion of said first notch intercepting the extended axis of said aperture to receive said lift cord when the blind is closed, another of said openings of each group being a second notch in the margin of the slat on the same side of the longitudinal center line of the slat as said aperture for the other end of said one cross tape, said second notch having a relatively narrow marginal entrance and having a dimension longitudinally of the slat substantially equal to the width of a cross tape, said first notches of the successive slats extending alternately in opposite directions from the extended axes of the corresponding apertures in the slats with said end portions of the first notches of the successive slats in vertical alignment, said second notches of the successive slats being likewise positioned alternately on opposite sides of the axes of the corresponding apertures of the slats.

2. A full-closure Venetian blind, comprising: a vertical series of horizontal slats; at least two ladders supporting said slats, each of said ladders comprising a front vertical supporting tape and a rear vertical supporting tape interconnected by a plurality of vertically spaced cross tapes, said cross tapes being narrower than the supporting tapes and staggered alternately on opposite sides of the center lines of the supporting tapes; lift cords passing down through said

ladders between said alternately staggered cross tapes; a plurality of vertically spaced horizontal slats of curved cross sectional configuration supported by said cross tapes, each of said slats having a group of openings for cooperation with each of said ladders and the corresponding lift cord, one of said openings of each group being an elongated aperture for said lift cord with the axis of the aperture extending transversely of the slat, said aperture being positioned to one side of the longitudinal center line of the slat, another of said openings of each group being a first notch in the margin of the slat to the other side of the longitudinal center line of the slat for one end of one said cross tape, the dimension of said first notch longitudinally of the slat being greater than the width of a cross tape but less than twice such width, with an end portion of said first notch intercepting the extended axis of said aperture to receive said lift cord when the blind is closed, another of said openings of each group being a second notch in the margin of the slat on the same side of the longitudinal center line of the slat as said aperture for the other end of said one cross tape, said second notch having a relatively narrow marginal entrance and having a dimension longitudinally of the slat substantially equal to the width of a cross tape, said first notches of the successive slats extending alternately in opposite directions from the extended axes of the corresponding apertures in the slats with said end portions of the first notches of the successive slats in vertical alignment, said second notches of the successive slats being likewise positioned alternately on opposite sides of the axes of the corresponding apertures of the slats; and an upper horizontal tilt bar rotatable about an axis longitudinally thereof, the front of said tilt bar being operatively connected with the front supporting tape of each ladder at a given distance from the uppermost cross tape of the ladder and the rear of the tilt bar being connected to the rear supporting tape of each ladder at a greater distance from the uppermost cross tape of the ladder, whereby the cross tapes are positioned substantially horizontally when said tilt bar is tilted upwardly and rearwardly from the horizontal.
